Primary Examiner — Susan Bennett Hattan*Assistant Examiner* — Marie Fast Horse(74) *Attorney, Agent, or Firm* — Norris McLaughlin & Marcus PA(57) **CLAIM**

The ornamental design for a packaging insert, as shown and described.

DESCRIPTION

FIG. 1 is a front and side perspective view of my packaging insert;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings depict environmental subject matter, are for illustrative purposes only, and form no part of the claimed design.

1 Claim, 4 Drawing Sheets(56)
